US00D626718S

(12) United States Design Patent
Turner

(10) Patent No.: US D626,718 S
(45) Date of Patent: * Nov. 9, 2010

(54) COMPRESSION SHORTS

(75) Inventor: David Turner, Beaverton, OR (US)

(73) Assignee: Nike, Inc., Beaverton, OR (US)

() Term: 14 Years

(21) Appl. No.: 29/352,351

(22) Filed: Dec. 18, 2009

(51) LOC (9) Cl. 02-01

(52) U.S. Cl. D2/712

(58) Field of Classification Search D2/712, D2/701, 700, 742, 704, 731, 738, 732, 733; 2/400, 404, 406-408, 267, 22, 23, 465; D29/100, D29/101.5

See application file for complete search history.

CLAIM

The ornamental design for compression shorts, as shown and described.

DESCRIPTION

FIG. 1 is a perspective view of compression shorts showing my new design;

FIG. 2 is a front view of the compression shorts shown in FIG. 1;

FIG. 3 is a rear view the compression shorts shown in FIG. 1;

FIG. 4 is a first side view the compression shorts shown in FIG. 1; and,

FIG. 5 is a second side view the compression shorts shown in FIG. 1.

The uneven broken line representations in FIG. 1-FIG. 5 are for illustrative purposes only and form no part of the claimed design.
